Application October 8, 1938, Serial No. 234,006
 In Germany October 5, 1937

7 Claims. (Cl. 235—59)

This invention relates to calculating typewriters having a plurality of vertical or column totalizers arranged on the paper carriage to travel therewith, and at least one crossfooter totalizer arranged on a slide which is guided on the machine frame.

A calculating typewriter of this type is described in the U. S. Patent No. 1,270,471. In such machines there is provided a locking mechanism for locking the control for the differential mechanism of the calculating typewriter if only one totalizer is in calculating position, that is, if only a vertical totalizer is in calculating position and the crossfooter totalizer is in its position of rest or if the crossfooter totalizer is in calculating position but no vertical totalizer is effective.

During a calculating operation the crossfooter totalizer is always carried along with that one of the vertical totalizers which is in calculating position, and is disengaged from this vertical totalizer when the vertical or column totalizer leaves the calculating position. The crossfooter totalizer thereupon jumps back to its position of rest to be picked up and carried along with the next vertical totalizer and so on. Calculating typewriters are commonly equipped with a tabulator mechanism for releasing the paper carriage for a column skipping movement. During such skipping of the paper carriage one or more of the vertical totalizers pass through the calculating position and the crossfooter totalizer is carried along by each successive vertical totalizer as the latter approaches the calculating position.

As the vertical totalizer completes its travel past the calculating position, the crossfooter totalizer is disengaged therefrom and the crossfooter springs back again to its position of rest, thus being continuously moved to and fro. Heretofore, this to-and-fro movement of the crossfooter totalizer has been prevented by providing means to retain the crossfooter totalizer in its extreme left-hand position, this means being connected to the tabulator mechanism. It becomes effective when a tabulator key is actuated and remains effective until the actuated key is released.

When the calculating typewriter is very rapidly operated, it can happen that a digit-key may be depressed immediately after releasing the depressed tabulator key. In such event, the digit-key may be depressed before the crossfooter totalizer has returned to its position of rest and thus a digit value can be introduced into the totalizers during the jumping-back of the crossfooter totalizer, the digit value being entered into

a wrong ordinal place of the crossfooter totalizer. Such miscalculations can arise because the above mentioned locking mechanism of said patent does not become effective until the crossfooter totalizer reaches its right-hand end position.

It is an object of the invention to prevent miscalculations of the kind mentioned. Accordingly, the invention comprises means for actuating a locking mechanism for a part of the actuating mechanism of the calculating typewriter in such a manner that this mechanism is locked during the jumping-back of the crossfooter totalizer.

According to the present invention this is achieved by providing control means on the slide of the crossfooter totalizer which control means is in continuous operative engagement with the locking mechanism for controlling it during movement of the slide.

An example of this mechanism embodying the invention is shown in the drawing, which illustrates diagrammatically the pertinent portions of a calculating typewriter,

Fig. 1 is a front view showing the parts in writing position before the slide of the crossfooter totalizer has been engaged by a vertical or column totalizer, and

Fig. 2 is a similar view, showing the parts in calculating position with the slide of the crossfooter totalizer engaged, through its pick up beam, by the active column or vertical totalizer.

The machine frame 1 is equipped with guides 2 on which a slide 3 can shift horizontally. The slide 3 is drawn to the right by a spring 4 and serves to carry a crossfooter totalizer 5. The slide 3 has an arm 6 carrying at the left-hand end a pivot pin 7 on which is mounted a pick-up beam 8 and a tongue 9. Tension springs 10 and 11 are provided between the beam 8 and the tongue 9 and between the beam 8 and the arm 6, respectively. The beam 8 has a lug 12 and the tongue 9 at its free left hand end, is provided with an upwardly projecting locking tooth or projection 9', these parts constituting in known manner a pair of jaws for releasably holding between them the ear 13' or 13'' depending from the vertical or column totalizer 15', 15'', respectively. Said column totalizers are mounted in endwise alignment on the paper carriage 14 to travel therewith.

A trip lever 17 pivoted at 16 to the machine frame is connected by a rod 21 with one arm of a bell crank lever 23 pivoted to the machine frame at 22, the other arm of which bell crank carries a stop member 24 serving to lock the operating shaft 25 of the differential mechanism 26 of the

machine against rotation, when interposed in front of an arm 27 on this shaft.

The above explained mechanism is old and well known in the art, as exemplified in the patent to Wahl, No. 1,270,471, wherein the rock or actuating shaft 71 with its finger 460, of Figs. 14, 16 and 21 may be considered as similar to applicant's actuating shaft 25, and Wahl's lever 283, link 468, and bell crank 465 may be considered as the equivalents of applicant's lever 17, connecting rod 21 and bell crank 23. Wahl also shows the cross footer totalizer, supporting slide and pick-up beam to which applicant has applied his improvements.

As heretofore stated, this mechanism is open to the objection that, in column skipping operations wherein the paper carriage with its column totalizers travels quickly relatively to the lug 12 of the pick-up beam 8, each column totalizer by-passed or skipped will engage the pick-up beam and swiftly draw the slide 3 with its crossfooter by a continuous motion to the extreme left hand limit of travel permitted the crossfooter. Upon reaching such extreme limit of its travel, corresponding to the units of cents position of the crossfooter, the pick-up beam and its lug will be disconnected from the by-passed column totalizers successively, whereupon the spring 4 will act to restore the crossfooter totalizer to its normal right hand limit of travel.

Particularly in those instances where the column totalizers are arranged closely together in end to end relation, and especially where a column totalizer of small capacity, as 15", lies closely adjacent to a column totalizer of wide capacity, the depending ear 13" of the narrow totalizer will catch and arrest the lug 12 on the pick-up beam 8, before the spring 4 will have had time to snap the lug, pick up beam and crossfooter totalizer from the left hand limits to the right hand limits of their travel, due to the fact that the paper carriage with its column totalizers is traveling freely in the opposite direction at the same time and under the influence of the powerful carriage feed spring drum (not shown).

If, under such conditions, a speedy operator, under the impression that the particular totalizer wheel of the selected column totalizer, is in its operative position, prematurely depresses a calculating key, the corresponding digit will be erroneously entered, not only into the crossfooter totalizer, but also into the particular column totalizer at that time traversing the calculating zone, since the presence of a column totalizer in the calculating zone releases all the automatic safeguards against its operation.

To remedy this possible erroneous entry of a digit, this invention provides means which enables the crossfooter totalizer to set the locking mechanism to its effective position at the very beginning of its spring-drawn return movement towards its normal right hand position, instead of at the end of such return movement, as in the prior art.

Thus, the possibility of improperly entering amounts in the column and crossfooter totalizers during the return travel of the crossfooter totalizer to its home position is prevented.

For this purpose, one end of a link 18 lying parallel with the connecting rod 21 is pivotally connected to the trip lever 17, the opposite free end of the link extending into the adjacent open end of a horizontal, hollow socket or sleeve 20 secured to the slide 3, preferably at the lower

end thereof. The lower face of the link rests loosely on the bottom of the internal cavity of the socket or sleeve, and an arched or hump-backed leaf spring 19 is fastened at one end to the upper face of the link, the height of the arched portion of the spring being greater than the space between the upper face of the link and the upper face of the internal cavity.

When the crossfooter totalizer 5 and its slide 3 are in their normal home positions, the socket or sleeve 20 is telescoped over the link 18 and spring 19 as far as it will go, compressing and flattening the spring so as to effect a strong frictional gripping action between the spring and its link 18, and the socket or sleeve 20.

The return spring 4 which is sufficiently strong to overcome the frictional resistance opposed by the leaf spring 19 in its contact with the wall of the cavity or bore of the socket 20, shifts the slide 3 with its crossfooter 5 and its sleeve 20 to their home positions, where they normally remain.

In so doing, the contact of the sleeve 20 with the leaf spring 19 connected to the link 18, and the resulting resistance opposed by the spring to the telescoping action of the sleeve 20, operates to rock the trip lever 17 clockwise. The trip lever, in turn, acting through the connecting rod 21, rocks the bell crank 23 counter-clockwise to interpose the stop member 24 into the path of the arm 27 on the actuating shaft 25.

The trip lever 17 by contact with the side wall of the machine frame 1, besides limiting the throw of the bell crank 23 and the effective position of the stop member 24, arrests farther travel of the link 18 and spring 19 to the right so that continued movement of the slide 3, and its crossfooter 5 towards their home positions telescopes the sleeve 20 of the slide over the spring 19 and link 18.

In operation, the lug 12 of the pick-up beam 8 is contacted by an ear, as 13', on a column totalizer travelling with the advancing paper carriage, as such column totalizer is entering the calculating zone. As the paper carriage continues its advance towards the left to traverse the active column totalizer across the calculating zone, the pick-up beam is drawn along to advance the slide 3 and crossfooter totalizer 5 relatively to its master wheel (not shown) and against the tension of the return spring 4, whereby digits entered in the column totalizer may be simultaneously entered in the crossfooter totalizer.

The socket or sleeve 20 advances with the slide 3 and because of the frictional engagement between the sleeve and the link 18, due to the compressed leaf spring 19, the link 18 is drawn to the left without lost motion between the sleeve 20 and link 18. The link 18, in turn, rocks the trip lever 17 counter-clockwise from the position shown in Fig. 1 to that shown in Fig. 2, and the trip lever, operating through the connecting rod 21, rocks the bell crank 23 clockwise to withdraw the stop member 24 from the path of the arm 27 on the actuating shaft 25.

In some machines, the paper carriage advances but a single letter space from the moment when it first picks up the lug 12 on the pick-up beam, to the moment when the stop member 24 is withdrawn to ineffective position, during which advance there is no relative movement between the sleeve 20 on the slide 3 and the link 18 connected to the trip lever 17.

Since the active column totalizer continues

to advance the pick-up beam 8, together with the slide 3 and its cross totalizer, the impositive connection between the slide and the trip lever 17 would continue to rock said lever and the thereto-connected bell crank an unnecessary extent, as well as impairing the basic inventive idea of this invention, to avoid which, the connecting rod 21 is provided with an abutment 21' arranged to contact the adjacent side wall of the frame 1 as the crossfooter totalizer completes its first step of advance, thereby arresting farther movement of the trip lever 17 counter-clockwise and of the bell crank 23 clockwise, and continued advance of the crossfooter, with its slide 3 and socket or sleeve 20, during and incident to the traverse of the column totalizer across the calculating zone, operates to withdraw the socket or sleeve relatively to the link 18 and its leaf spring 19. Such withdrawal of the sleeve relaxes the constriction or compression applied by the sleeve to the leaf spring, resulting in a lessening of the strength of the frictional engagement between the link and sleeve until, as the column and crossfooter totalizers advance to position their units wheels (not shown) at the calculating zone the grip is almost released, as indicated in Fig. 2 when a wide capacity column totalizer is in control of the pick-up beam.

As a result of the entry of the units digit into the column and crossfooter totalizers and more particularly, the printing of the corresponding digit, the paper carriage advances a single letter space, which movement disconnects the pick-up beam from the active column totalizer and the column and crossfooter totalizers pass beyond the calculating zones, in the manner set forth in the above mentioned Wahl patent.

The crossfooter totalizer return spring 4 immediately acts to restore the crossfooter and its slide and pick-up beam to their normal home positions, and the sleeve 20, because of the remaining slight impositive connection through the leaf spring 19 with the link 18, at the very beginning of the return travel of the crossfooter totalizer, shifts the trip lever 17 clockwise to restore the stop or blocking member 24 into the path of its coating stop arm 27, thus preventing the entry of a digit into either the column totalizer or the crossfooter totalizer during the return of the crossfooter totalizer to its home position.

This enables the crossfooter and its slide 3 to complete their return to home position, during which the socket 20 carried by the slide telescopes over the spring 19 and link 18, as shown in Fig. 1.

A further improvement on the structure disclosed in Wahl Patent 1,270,471 above mentioned, resides in the provision of means to insure that the locking mechanism shall be rendered ineffective, so as to permit the entry of digits into the column and crossfooter totalizers in those instances where a column totalizer of narrow capacity lies to the right of, and in substantial end-to-end relation with a column totalizer of wide capacity.

In such instances, the ear 13', (Fig. 1) on the left hand column totalizer of wide capacity will have drawn the pick-up beam 8 and the crossfooter totalizer connected therewith nearly to their extreme left-hand positions, to enable the entry of the units digit of an item in the units wheel of the wide capacity column totalizer 15' and in the units wheel of the crossfooter totalizer 5. The usual let-off or letter spacing step of the

paper carriage with its column totalizers following the printing of said units digit, operates in the manner disclosed in the Wahl patent, above mentioned, to disengage the pick-up beam 8 from the ear 13' of the wide capacity column totalizer, whereupon the crossfooter return spring 4 which is superior to the leaf spring 19, operates to restore the crossfooter totalizer 5 and slide 3 towards normal position.

Now, assume that it is desired to skip a wide capacity column totalizer, as 15' and to pick up a narrow column totalizer as 15" located in close juxtaposition to the wide totalizer. As the paper carriage advances on its column skipping operation, the ear 13' of the wide capacity column totalizer to be skipped, will engage the pick-up beam 8, and advance the crossfooter 5 and its slide 3 just as when an amount is to be entered, and in so doing, by the time the units wheel of the wide capacity column totalizer is brought to the calculating zone, the socket 20, carried by the crossfooter slide 3 will have been slid almost out of engagement with the friction spring 19, so that, before the disengagement of the pick-up beam 8 from the wide capacity column totalizer, the socket has a weakened frictional engagement with the spring 19.

Immediately upon such release of the pick-up beam 8 from the wide capacity column totalizer, the crossfooter return spring 4 snaps the crossfooter and its pick-up beam towards the right, but because of the distance through which the wide column totalizer has drawn the pick-up beam and crossfooter to the left, and also because of the close proximity of the narrow capacity column totalizer 15" to the wide capacity column totalizer 15', the ear 13" of the narrow capacity totalizer engages the retracting pick-up beam 8 after the slide 20 at the initiation of the return travel of the crossfooter has operated through its contact with the spring 19 to shift the locking mechanism to its effective position, but before the spring 4 has had time to return the crossfooter and pick-up beam to their home positions and thus establish a firm frictional engagement between the socket 20 and the spring 19.

Not only are the pick-up beam 8 and crossfooter 5 arrested by the engagement of the ear 13" with the shoulder 12 of the pick-up beam, but the carriage, still operating on its column skipping advance, immediately reverses the direction of travel of the pick-up beam and crossfooter, to bring the narrow column totalizer to the calculating zone.

Naturally this abrupt arrest and reversal imparts a shock to the crossfooter and its socket 20 traveling with the crossfooter in the opposite direction, and since the frictional engagement between the socket and its friction spring 19 has already been reduced by the extreme leftward travel of the wide capacity column totalizer, pick-up beam, crossfooter and socket there is a possibility that there will not be a sufficiently strong frictional engagement re-established between the socket and the spring by the partial return of the crossfooter and its socket, to draw the lever 17 to the left and effect displacement of the stop member 24 from the path of the stop arm 27 on the actuating shaft 25, in which event, no entry of items on either the narrow column totalizer or the crossfooter could occur, even though the narrow column totalizer and the crossfooter are in position for the entry thereinto of the first digit of an item.

To obviate this possibility when the narrow

column totalizer is selected for the entry of items therein, the usual tongue or latch 9 is provided with a depending node 9' normally lying directly over the depressed median portion of a release lever 28 pivoted to the machine frame at 28 and lying beneath and in substantial parallelism with the horizontal arm of the bell crank 23. (Fig. 1.)

The depressed portion of the release lever 28 lies intermediate the ends of said release lever, such end portions or arms lying in a higher plane with the right hand arm closely adjacent the lower edge of the horizontal arm of the bell crank 23.

In operation, the ears 13' and 13'' of each column totalizer 15', 15'' as they pass in succession over the upwardly extending tooth 9'' of the latching tongue 9, temporarily depress the tongue with its node 9', the tongue being immediately restored by its spring 11 to take behind the ear.

When the crossfooter totalizer 5 is in its home position, such depression is without effect upon the releasing lever 28 because the depending node 9' lies over the depressed central portion of said lever. As the active column totalizer advances the crossfooter 5 step by step past the usual master wheel, as explained in the Wahl patent cited, the pick-up bar 3 and tongue 9 advance, causing the node 9' of the tongue to wipe over the incline connecting the depressed central portion of the release lever 28 with its left hand arm, thereby rocking the release lever counter-clockwise and causing its rear end to follow up the horizontal arm of the bell crank 23 which is simultaneously rocked by the crossfooter totalizer as it advances, through its frictional connection with the trip lever 17, to displace the stop member 24 from the path 10 of the co-acting stop arm 21.

In regular operations, the node 9' merely idly rocks the release lever 28.

In those instances wherein the pick-up beam 6, after having been advanced to the left a considerable distance and then released from its column register, is intercepted on its return before it reaches its home position, by the ear of a column register advancing in the opposite direction, the node 9' of the latching tongue 9 at the time of such interception will lie over some portion of the terminal dwell portion of the left hand arm of the release lever 28, depending upon the extent to which it was advanced by the wide capacity totalizer movement.

The return of the pick-up beam 6 with its crossfooter 5, slide or truck 3 and socket 20, under the influence of the crossfooter spring 4, for a distance of one step has enabled the socket 20 and its friction spring connection 19 with the link 18, to rock the trip lever 17 clockwise, and through the connecting bar 21, to rock the bell crank 23 counter-clockwise and interpose the locking member 24 into the path of the arm 27 on the actuating shaft 25 to prevent operation of the machine.

But the gripping action between the socket 20 and the spring 19 due to the immediately preceding extensive advance of the socket relatively to its friction spring 19, may be insufficient at this time as heretofore explained, to draw the lever 17 counter-clockwise and through the recited train, displace the locking member 24 from the path of the arm 27 of the actuating shaft.

However, the ear 13'' on the intercepting column totalizer of narrow capacity, as it wipes over the upwardly projecting tooth 9'' of the pick-up

beam latch 9, rocks said latch downwardly or counter-clockwise to press the node 9' of the latch against the terminal dwell portion on the left hand arm of the release lever 28, rocking said lever counter-clockwise to force the right-hand arm of the release lever against the lock-controlling bell crank 23, which rocks the bell crank clockwise to withdraw the locking member 24 from the path of the arm 27 on the actuating shaft 25 and thus free the machine for operation independently of the frictional socket and humped spring connection.

As soon as this operation is effected, the ear 13'' of the column totalizer escapes past the tooth 9'' of the pick-up beam latch 9 which, thus released, returns to its normal position under the action of the spring 11 and has no further effect on the release lever 28.

We claim as our invention:

2. In a typewriting-accounting machine of the class described, having a frame, and a traveling carriage; a column totalizer mounted on the carriage; and a cross footer totalizer shiftably mounted on the frame; the combination with a pick-up beam to releasably connect the column and cross footer totalizers to enable the column totalizer, as it approaches its calculating zone, to simultaneously advance the cross footer totalizer from its home position; means to restore the cross footer totalizer and pick-up beam to home position upon release of the pick-up beam from the column totalizer as the latter escapes past the calculating zone; an actuating means; and a locking mechanism normally effective to lock the actuating means against operation; of a connection capable of extension and contraction, to couple the crossfooter totalizer and the locking mechanism, and under the control of the crossfooter totalizer; and means inferior to the crossfooter totalizer restoring means to maintain frictional engagement of the connection in any of its relative positions, to enable the crossfooter totalizer, at the beginning of its advance simultaneously with the column totalizer, to render ineffective the locking mechanism through operation of said connection in one direction, and at the beginning of the return of the crossfooter totalizer toward home position, to restore the locking mechanism to its effective position.

2. In a typewriting-accounting machine of the class described, having a frame, and a traveling carriage; a column totalizer mounted on the carriage; and a crossfooter totalizer shiftably mounted on the frame, the combination with a pick-up beam to releasably connect the column and crossfooter totalizers to enable the column totalizer, as it approaches its calculating zone, to simultaneously advance the crossfooter totalizer from its home position; means to restore the crossfooter totalizer and pick-up beam to home position upon disconnection of the pick-up beam and column totalizer as the latter escapes past the calculating zone; an actuating means; and a locking mechanism normally effective to lock the actuating means against operation; of a connection capable of extension and contraction, to couple the crossfooter totalizer and the locking mechanism, and under control of the crossfooter totalizer, said connection including mutually transcurvative members; means to maintain frictional engagement of the transcurvative members to enable the crossfooter totalizer, at the beginning of its advance, to shift the locking mechanism to its ineffective position, and at the be-

ginning of its return to home position, to restore the locking mechanism to its effective position; and means to arrest continued release movement of the locking mechanism after it has been shifted to its ineffective position, while the crossfooter totalizer continues its advance synchronously with the column totalizer with a consequent extension of the connection, said connection being contracted by the crossfooter totalizer on its return to home position subsequently to the restoration of the locking means to its effective position.

3. In a typewriting-accounting machine of the class described, having a frame and a traveling carriage; a column totalizer mounted on the carriage; and a crossfooter totalizer shiftably mounted on the frame; the combination with a pick-up beam connected with the crossfooter totalizer for engagement by, and disengagement from, the carriage, to enable the column totalizer and crossfooter totalizer to advance simultaneously; means to restore the crossfooter totalizer and its pick-up beam to home position upon disconnection of the pick-up beam and the column totalizer, as the column totalizer escapes past the calculating zone; an actuating means; and a locking mechanism normally effective to block the operation of the actuating means; of a two-part telescopic connection to couple the crossfooter totalizer and the locking mechanism; a resilient member to maintain frictional engagement between the parts of the connection in any of their relative positions; and means connected with one of the parts of said connection and co-acting with said frame to arrest said part, following the engagement of the pick-up beam and the column totalizer, to enable relative movement between the parts of the telescopic connection during farther simultaneous travel of the crossfooter and column totalizers; said resilient member effective to enable the crossfooter totalizer at the beginning of its advance with the column totalizer, to shift the locking mechanism to its ineffective position, through said connection, and at the beginning of its return travel, to restore the locking mechanism to its effective position.

4. In a typewriting-accounting machine of the class described, having a frame and a traveling carriage; column totalizers mounted in succession on the carriage; and a crossfooter totalizer shiftably mounted on the frame, the combination with a pick-up beam to releasably connect the column totalizers successively with the crossfooter totalizer as the column totalizers respectively approach the calculating zone, to advance the crossfooter from its home position; means to restore the crossfooter totalizer and pick-up beam to home position upon disconnection of the pick-up beam and column totalizer as the latter escapes past the calculating zone; an actuating means; and a locking mechanism to lock the actuating means against movement; of a connection capable of extension and contraction, to couple the crossfooter totalizer and the locking mechanism, and under control of the crossfooter totalizer; means inferior to the crossfooter restoring means to apply friction to the connection, to enable the crossfooter totalizer, at the beginning of its advance with the column totalizer to shift the locking mechanism to its ineffective position, and at the beginning of its return toward home position, to restore the locking mechanism to its effective position; an aux-

iliary member operable upon the locking mechanism to release the latter; and means on said pick-up beam operable by the column totalizers successively to actuate the auxiliary release member after an interception of the pick-up beam before its return to home position, to cause the auxiliary member to release the locking mechanism in the event of the failure of said connection to return a sufficient distance from its previous advance.

5. In a typewriting-accounting machine of the class described, having a frame and a traveling carriage, column totalizers of various capacities mounted on the carriage in any desired order, and a cross footer totalizer shiftably mounted on the frame, the combination with a pick-up beam to releasably connect the column totalizers successively with the cross-footer totalizer during the travel of each column totalizer across the calculating zone, which advance the cross-footer totalizer different extents from its home position; means to restore the crossfooter totalizer and pick-up beam to home position upon the disconnection of the pick-up beam and the successive column totalizers as the latter escape past the calculating zone; an actuating means; and a locking mechanism normally effective to lock the actuating means against operation; of a frictional connection capable of extension and contraction to couple the cross-footer totalizer and the locking mechanism, and under the control of the cross-footer totalizer, to normally enable the crossfooter totalizer, at the beginning of its advance with a column totalizer, to shift the locking mechanism to its ineffective position, and at the beginning of its return towards home position, to restore the locking mechanism to its effective position; a normally idle auxiliary member operable independently of the crossfooter totalizer to shift the locking mechanism to its ineffective position; and means on said pick-up beam operable by any of the column totalizers to actuate the auxiliary member in case of the interception of the pick-up beam and crossfooter during their return to home position after the crossfooter has rendered the locking mechanism effective through said connection, but while the connection is inadequate to shift the locking mechanism to its ineffective position upon the ensuing abrupt reversal of the direction of travel of said cross-footer totalizer by the advancing active column totalizer, said auxiliary member having a dwell portion substantially co-extensive with the farthest advance travel of the crossfooter totalizer, for engagement by the actuating means on the pick-up beam at the time when said active column register upon its advance, intercepts the return of the pick-up beam and crossfooter preparatory to synchronously advancing said pick-up beam and crossfooter.

6. In a typewriting-accounting machine of the class described, having a frame and a traveling carriage, column totalizers of various capacities mounted on the carriage in any desired order and a cross-footer totalizer shiftably mounted on the frame, the combination with a pick-up beam to releasably connect the column totalizers successively with the cross-footer totalizer during the travel of each column totalizer across the calculating zone, which advance the cross-footer totalizer different extents from its home position; means to restore the cross-footer totalizer and pick-up beam to home position upon the disconnection of the pick-up beam and the successive column totalizers as the latter escape

past the calculating zone; an actuating means; and a locking mechanism normally effective to lock the actuating means against operation; of a frictional connection capable of extension and contraction to couple the cross-footer totalizer and the locking mechanism, and under the control of the cross-footer totalizer, to normally enable the cross-footer totalizer, at the beginning of its advance with a column totalizer, to shift the locking mechanism to its ineffective position, and at the beginning of its return towards home position, to restore the locking mechanism to its effective position; a normally idle auxiliary member operable independently of the crossfooter totalizer to shift the locking mechanism to its ineffective position; and means on said pick-up beam operable by any of the column totalizers to actuate the auxiliary member in case of the interception of the pick-up beam and crossfooter during their return to home position after the cross-footer has rendered the locking mechanism effective through said connection, but while the connection is inadequate to shift the locking mechanism to its ineffective position upon the ensuing abrupt reversal of the direction of travel of said cross-footer totalizer by the advancing active column totalizer; said auxiliary member having a clearance normally in register with the actuating means on the pick-up beam, to render ineffective said actuating means on the pick-up beam when the cross-footer, totalizer and pick-up beam have nearly returned to their home positions.

7. In a typewriting-accounting machine of the class described, having a frame and a traveling carriage, column totalizers of various capacities mounted on the carriage in any desired order and a cross footer totalizer shiftably mounted on the frame, the combination with a pick-up beam to releasably connect the column totalizers successively with the cross-footer totalizer during the travel of each column totalizer across the calculating zone, which advance the cross footer totalizer different extents from its home position; means to restore the crossfooter totalizer and pick-up beam to home position upon the disconnection of the pick-up beam and the successive column totalizers as the latter escape past the calculating zone; an actuating means; and a locking mechanism normally effective to lock the actuating means against operation; of a frictional connection capable of extension and contraction to couple the cross footer totalizer and the locking mechanism, and under the control of the cross-footer totalizer, to enable the cross footer totalizer, at the beginning of its advance with a column totalizer, to shift the locking mechanism to its ineffective position, and at the beginning of its return towards home position, to restore the locking mechanism to its effective position.
